UNITED STATES PATENT OFFICE.

CHARLES ALFRED SAMUELL, OF HEDGESVILLE, MONTANA.

WELL TOOL.

Application filed May 10, 1921. Serial No. 468,323.

To all whom it may concern:

Be it known that I, CHARLES A. SAMUELL, a citizen of the United States, residing at Hedgesville, in the county of Wheatland and 5 State of Montana, have invented new and useful Improvements in Well Tools, of which the following is a specification.

This invention comprehends the provision of a well fishing tool designed to take an effective purchase upon the bit so that the 10 latter can be easily removed without any danger of the bit becoming casually separated from the tool when the latter is being used.

15 Another object of importance resides in the provision of a guide designed for use in conjunction with the tool in such instances where the bit is not arranged in a true vertical position to be engaged by the tool, the 20 guide being utilized to position the bit in a manner so that the tool may be used for the purpose stated.

The nature and advantages of the invention will be better understood when the following detailed description is read in connection with the accompanying drawings, the invention residing in the combination, construction, and arrangement of parts as claimed.

30 In the drawings forming part of this application, like numerals of reference indicate similar parts in the several views and wherein:

Figure 1 is a side elevation of the guide.

35 Figure 2 is a view of the guide showing the relation of the blade-like members with each other.

Figure 3 is a view in elevation of the tool.

Figure 4 is a longitudinal sectional view 40 therethrough.

Figure 5 is a view showing the offset position of the bit with the guide arranged above the bit just prior to performing its function.

45 Figure 6 is a sectional view taken through the tool and guide.

Referring to the drawings in detail, 10 indicates a hollow tubular member forming the guide above referred to and from the 50 end of which member projects the spaced parallel arms 11 the latter terminating to provide curved blade-like members 12 which are normally arranged in contacting engagement as at 13, the blades however, being de- 55 signed to provide a flared entrance passage between the blades as at 14.

The tool is indicated at 15 and also consists of a hollow tubular member, a portion of the bore being of conical formation as at 16 and merging into a straight portion 17. 60 The tool is bored from its upper end as at 18, these bores being convergently disposed and opening into the straight portion 17 of the bore of the tool as illustrated. Arranged within each bore 18 is a ball 19 65 which is normally held adjacent the lower ends of the bores, by means of coiled springs 20 which are also positioned within the bores or passages 18. The tool is provided with a yoke 21 at its upper end by means of 70 which it is associated with a cable utilized in lowering the tool into the well in the usual manner. In practice, the tool is lowered into the well, the bit entering the lower end of the tool which by reason of its conical formation allows the tool to pass freely over the bit until the latter is brought into contact with the balls 19. As the latter are yieldably supported within the passages 18, 75 they are moved upwardly to allow the bit to pass into the straight portion 17 of the bore, with the balls 19 arranged about the bit, so that when a pull is exerted upon the tool in an effort to remove the tool from the well, the balls 19 being forced downwardly by 80 means of the springs 20 obtain an effective purchase upon the bit so that it cannot become casually separated from the tool incident to its removal from the well. 85

In some instances, the bit falls to one side or the other of the well opening, and assumes the position illustrated in Figure 5, and in which position, the tool cannot be associated with the bit. In such cases, the guides such as illustrated in Figures 1 and 90 2 is used in connection with the tool, the guide 10 being of a diameter to slidably receive the tool 15. The guide is lowered into the well slightly in advance of the tool 15, and the members 12 of the guide pass over the bit when it is in the position illustrated in Figure 5. The guide is lowered into the well by means of a cable independently of the cable which is used in connection with the tool, and after the guide has passed beyond the bit, the guide is elevated during which time the blade-like members 12 serve to move the bit from the position shown in Figure 5 to a true vertical position, holding it in this position while the tool 15 is lowered to engage the bit in the manner above described. 95 100 105 110

While it is believed that from the foregoing description the nature and advantages of the invention will be readily apparent, I desire to have it understood that I do not limit myself to what is herein shown and described, and that such changes may be resorted to when desired as fall within the scope of what is claimed.

What I claim is:

10 A device of the character described comprising in combination, a tubular member of uniform diameter throughout its length and open at both ends, spaced parallel arms

projecting from one end of the member, curved blade-like members supported by the lower extremities of said arms and forming an integral part thereof, said blade-like members contacting at a point adjacent the upper ends thereof, and shaped to provide a flared entrance passage between said blades, and a lifting device including a second tubular member adapted to be received by the first mentioned tubular member and arranged above the latter.

In testimony whereof I affix my signature. 25
CHARLES ALFRED SAMUELL.
